UNITED STATES PATENT OFFICE.

JAMES W. TAYLOR, OF SAN ANTONIO, TEXAS.

PUMPING APPARATUS.

Application filed March 16, 1925. Serial No. 15,760.

To all whom it may concern:

Be it known that I, JAMES W. TAYLOR, a citizen of the United States, residing at San Antonio, in the county of Bexar and State 5 of Texas, have invented certain new and useful Improvements in Pumping Apparatus, of which the following is a specification.

This invention relates to improvements in apparatus for effecting the removal of 10 liquids from oil wells, and has for its principal object the provision of means for employing the natural gas of a well for the purpose of effecting the pumping or elevation of the liquid after the natural flow of 15 the well has ceased.

Another object of the invention resides in the provision of apparatus of the character aforesaid wherein is embodied a well casing and a flow line, the flow line, at a suitable 20 point in its length, being provided with a hood member having an open lower end and a closed upper end, the said hood member being carried by the flow line and situated between the flow line and the casing, there 25 being an improved valve mechanism between the upper closed end of the hood member and the flow line, the arrangement being such that the hood member will entrap the natural gases arising from the well 30 and, through the medium of the fluids above the hood member, maintain such gases in a state of compression, whereby upon the opening of the valve mechanism such gas will be permitted to enter the flow line at 35 a point wherein immediate expansion of the gas is prevented but wherein the gas is permitted to rise in the flow line and subsequently expand for liquid expelling purposes.

40 It is a further object of the invention to provide means of a rotatable character for effecting the operation of the valve mechanism and to govern the extent of gas flow into the flow line or tubing of the well.

45 With these and other objects in view, as will appear as the description proceeds, the invention consists in the novel features of construction, combinations of elements and arrangements of parts hereinafter to be 50 fully described and pointed out in the appended claims.

In the accompanying drawings:

Figure 1 is a vertical sectional view taken through the upper end of the oil pumping 55 apparatus comprising the present invention,

Figure 2 is a vertical sectional view taken through the flowing hood and valve mechanism employed in carrying out the invention, 60

Figure 3 is a transverse sectional view on the line 3—3 of Figure 2.

Referring more particularly to the drawings the numeral 1 designates the casing of an oil well, which is of standard construction and is inserted into the well in the usual manner. Through the casing there extends a flow line 2, which leads to the bottom of the casing and is provided with an open lower end (not shown) into which the oil flowing naturally from the well is permitted to arise. The upper end of the casing 1 is provided with a head 3, which is shouldered as at 4 for the reception of a packing casing 5. This casing is provided with an annular shoulder 6, arranged to seat upon a gasket 7 carried by the shoulder 4. The shoulder 6 is annularly beveled as at 8 and is adapted to engage with the inner ends of set screws 9 carried by the casing 5. 75 Manifestly by threading the screws 9 inwardly, pressure may be applied to the casing 5 to firmly seat the latter upon the gasket 7 so as to prevent undue gas escape from the casing 1. The lower end of the 80 casing 5 is inwardly shouldered as at 10, and receives a packing material 11, which tightly surrounds the flow line 2. The upper internal portion of the casing 5 is threaded as at 12 for the reception of a 85 gland nut or bushing 13, which may be tightened downwardly into engagement with the packing 11 so as to press the latter firmly 90 into sealing engagement with the packing 11. This construction serves to insure the 95 retention of gas within the casing 1 and prevents their accidental release. This is important in that the natural gas of the well is used as the operating fluid for effecting the elevation of the liquid, and therefore 100 it is essential that accidental escape of the gas will be prevented.

The casing may be provided with an outlet 14, which is controlled by means of a valve 15 which when open may permit of 105 the controlled escape of the gas from the casing. The flow line 2 extends upwardly above the packing 11 to a suitable point of liquid discharge, and is supported and braced by means of the pipe fittings or connections 16, which serve to produce a rigid frame structure, as shown in Figure 1. The 110

upper end of the bushing 13 constitutes a race-way or seat for the reception of anti-friction bearings 17, which serve to support a hand wheel 18, which is fast on the tubing 5 by a set screw 19 or other equivalent means. The flow line is provided with a collar 20 which rests upon the upper end of the hub of the wheel 18. The weight of the flow line is suspended within the casing and its weight 10 is directed about the bearing 17 in order that by grasping the wheel 18, the said flow line may be rotated.

At a suitable point or level above its lower end the flow line is divided for the reception 15 of a flowing hood designated generally by the numeral 21. The hood 21 consists of a cap sleeve 22 which is internally threaded so as to be vertically adjustable upon threads 23 carried by one of the sections 24 of the 20 flow line. The upper end of the cap sleeve 22 is exteriorly threaded as at 25 for the reception of a nut 26, which acts to maintain a packing ring 27 compressed around the exterior surface of the pipe section 24 so 25 as to prevent fluid seepage through the threads 23. The lower end of the cap sleeve 22 is threaded for the reception of the upper end of a tubular hood casing 28 which is of any suitable length, but possesses a 30 diameter less than the internal diameter of the casing 1 so as to permit fluid flow between the outer wall of the hood casing 28 and the inner wall of the well casing 1. It will be observed that the inner wall of the 35 hood casing 28 is spaced in the exterior wall of the axially disposed flow line, so that there will be a gas storage space in the upper closed end of the hood casing to permit of the accumulation and storage of the natural 40 gas arising from the well.

The cap sleeve 22 has its lower end interiorly threaded for the reception of the upper end of a tube 29 which has its lower portion perforated as at 30 for the purpose 45 of establishing communication and fluid flow between the upper closed end of the hood casing and the flow line. The internal lower portion of the tube 29 is shouldered as at 31 against which is positioned the enlarged 50 body 32 of a nozzle 33, which is situated in the flow line and through which the oil or liquid arising from the well is directed.

Secured to the lower end of the pipe section 24 is a second nozzle section 34 provided internally with a tapering port 35 into which the nozzle 33 extends, and the section 34 is of a length as to cooperate with the perforations or passages 30 in the tube 29 for the purpose of governing fluid flow between 55 the hood and the flow line. It will be seen that upon the rotation of the flow line, by the manipulation of the wheel 18, vertical travel will be imparted to the hood 28 by reason of the threaded connection 60 which exists between said hood and the pipe

section 24. Since the tube 29 is attached to and travels in unison with the hood member it will be seen that there is relative movement between said tube and the stationary nozzle section 34. By this means the opening and closing of the passages 30 can be readily effected to control the flow of the elevating gas or fluid into the flow line. The threads connecting the section 24 of the flow line with the hood member are of the left hand type, and are purposely made this way so that the rotation of the flow line will not effect the loosening of any of the threaded joints, between the sections of the flow line, above the hood member. When the hood 70 member has been elevated to its maximum extent it will be seen that the lower curved edge 35', around the skirt of the nozzle section 34 will be forced into engagement with the annularly beveled surface 36 of the nozzle section 33, thereby closing the flow line 75 against the entrance of fluid from the hood 28. It will be observed, upon reference to Figure 2, that the nozzle section 33 rests upon a yieldable gasket or seat 37, which is 80 maintained in its operative position within the lower end of the tube 29 by means of a threaded plug 38, from which the lower portion of the flow line is suspended. In the event, therefore, that there is not a perfect seating relation between the edge 35' and the beveled surface 36, it will be seen 85 that the gasket 37 will compensate for irregularities existing in the seating of the valve, allowing the nozzle section 33 a limited degree of movement so that the edge 35' will be firmly pressed into engagement with the surface 36 around the full circumference of the latter. The extreme lower end of the hood casing 28 is provided with outwardly pressed, torsional guide members 39, which cooperate with the inner wall 90 of the casing and to prevent rotation of the hood casing when the flow line is rotated to operate the valve mechanism, also, the said guide members serve to permit the hood casing to be dropped into the well without striking shoulders and obstructions 95 therein and interfering generally with the downward movement of the casing. 100

In operation, the hood casing is forced into the well to assume the position disclosed substantially in Figure 2. The natural gas liberated from the liquid within the well is permitted to arise in the hood 110 28 and is confined or entrapped therein, and it will be observed that the liquid in the casing 1, above the hood member, serves to maintain the gas as accumulated in the hood 115 in its natural compressed state, or in other words the gas is prevented from expanding. It will now be seen that when the valve mechanism has been opened to permit of the flow of the fluid through the perforations or 120 passages 30, that the gas contained in the 125 pipe section 24 will expand and force the hood 130 casing 28 upward, thereby causing the rotation of the flow line, and the opening and closing of the passages 30.

- hood member will be permitted to circulate into the flow line. Due, however, to the column of fluid in the flow line, above the valve mechanism, the gas entering the flow line is still maintained in its compressed state and is not permitted to expand violently and suddenly, as this would result in the "cutting" of the oil. Expansible gas thus entering the flow line is permitted to rise by virtue of its natural flow in minute bubble form, within the flow line, until the top of the flow line is near when, due to the decrease of the hydro-static pressure, the gas bubbles gradually expand and their upward movement is accelerated. When the top of the flow line is reached the gas bubbles have expanded until the diameter thereof is that of the flow line, and due to the rapid and successive rise of these bubbles, the liquid above the same is displaced and forced from the flow line, substantially after the manner of a piston moving in a cylinder. It will be seen that by operating the wheel 18 the quantity of gas entering the flow line may be readily controlled so that the proper amount of gas may be admitted into the flow line proportionate to the amount of liquid contained in the flow line above the hood.
- 30 What is claimed is:
1. In oil well pumping apparatus, a casing, a flow line in said casing, a gas collecting hood around the flow line, said hood including a passage between the upper portion thereof and said flow line, and a vertically adjustable valve for governing fluid flow through said passage.
  2. In oil well pumping apparatus, a casing, a flow line in said casing, a gas collecting hood carried by said flow line, an entry between said hood and flow line, and means permitting of relative longitudinal travel between said hood and the upper part of said flow line to regulate fluid flow through said entry.
  3. In an oil well, a flow line including upper and lower sections, a hood carried in connection with one of said sections and surrounding said flow line, an entry establishing communication for fluid flow between said hood and flow line, and means permitting of relative longitudinal movement between the upper and lower sections of said flow line to regulate fluid flow through said entry.
4. In apparatus of the character set forth, a flow line including upper and lower sections, a hood having a threaded connection with the upper of said sections and surrounding said flow line, an entry establishing communication between said hood and said flow line, and means permitting of the rotation of the upper section of said flow line to move said hood vertically to open and close said entry.
5. In apparatus of the character set forth, a flow line including upper and lower sections, a hood having its upper end threaded to the lower end of the upper section of said flow line, the lower section of said flow line being suspended from said hood, an entry establishing communication between the interior of said hood and said flow line, means operable upon relative longitudinal movement between said hood and the upper section of said flow line to regulate fluid flow through said entry, and means therein to prevent rotation of said hood during the rotation of the upper section of the flow line.
6. In apparatus of the character set forth, a flow line including a rotatable upper section, a hood having threaded connection with said upper section and including a substantially closed chamber surrounding said flow line, the inner wall of said chamber being provided with a port, and means operable upon the rotation of the upper section of said flow line to effect longitudinal travel on the part of said hood to raise and lower the latter relatively to the upper section of the flow line so as to bring said port into and out of registration with the lower end of said upper section to regulate fluid flow from said chamber into the flow line.

In testimony whereof I affix my signature.

JAMES W. TAYLOR.
